DESIGN FOR A TOOTHBRUSH

Edward G. Norton, Springfield, Mass.

Application July 22, 1939, Serial No. 86,182

Term of patent 14 years

To all whom it may concern:

Be it known that I, Edward G. Norton, a citizen of the United States, residing at Springfield, in the county of Hampden and State of Massachusetts, have invented a new, original, and ornamental Design for a Toothbrush, of which the following is a specification, reference being had to the accompanying drawing, forming part thereof.

Fig. 1 is a top plan view of a toothbrush embodying my new design;

Fig. 2 is a side elevational view of the same; and

Fig. 3 is a perspective view of the same; Fig. 4 is a section taken on the line 4—4, Fig. 1; Fig. 5 is a section taken on the line 5—5, Fig. 1.

The ornamentation of the toothbrush shown on the drawing comprises a series of interiorly positioned fluorescent markings or sections arranged obliquely to the sides of the toothbrush.

What is claimed is:

The ornamental design for a toothbrush, substantially as shown and described.

EDWARD G. NORTON.
